UNITED STATES PATENT OFFICE

HERBERT H. BLACKWELL, OF KENBRIDGE, VIRGINIA.

ADDING-MACHINE.

1,202,781.

Specification of Letters Patent. Patented Oct. 31, 1916.

Application filed July 31, 1912. Serial No. 712,527.

To all whom it may concern:

Be it known that I, HERBERT H. BLACKWELL, a citizen of the United States, residing at Kenbridge, in the county of Lunenburg and State of Virginia, have invented new and useful Improvements in Adding-Machines, of which the following is a specification.

This invention relates to adding machines. 10 The primary object of the invention is to provide an adding machine having improved means for inking the type and printing the characters upon the paper strip directly from the type.

15 A further object of the invention is to provide an adding machine embodying a minimum number and novel construction and relationship of working parts adapted to be quickly and conveniently operated.

20 A still further object of the invention is to provide an adding machine embodying novel and improved printing mechanism and novel and improved means whereby such printing mechanism is readily adjustable to print the numbers of a row of figures and the totals of a column of rows of figures and to be returned to normal position.

25 With these and other objects in view, the invention consists of the features of construction, combination and arrangement of parts, hereinafter fully described and claimed, reference being had to the accompanying drawings, in which—

Figure 1 is a side elevation of an adding machine embodying my invention with one side of the casing removed and the parts appearing in normal position. Fig. 2 is a horizontal transverse section on the line 2—2 of Fig. 1. Fig. 3 is a vertical transverse section on the line 3—3 of Fig. 1. Fig. 4 is a vertical transverse section on the line 4—4 of Fig. 1. Fig. 5 is a vertical longitudinal section on the line 5—5 of Fig. 3, showing the parts in printing position. Fig. 45 6 is a sectional plan view on line 6—6 of Fig. 1.

Referring to the drawings, 1 designates a casing having a generally sloping top 2 provided at its upper rear portion with a partially circular inclosure 3 for a paper roll 4 mounted upon a shaft or spindle 5. The top 2 is formed adjacent said inclosure with a slot 6 for the outward feed of the paper strip. The end 7 of this strip passes from the body of the roll 4 around suitable guide rolls 8 and beneath a platen or printing roll

9 and thence outward through the slot. The shaft of the roll 9 has fixed thereto a pair of ratchet wheels 10, each engaged by a feed dog 11 carried by one arm of a bell-crank lever 12, the opposite arms of which levers are connected for movement in unison by a rod or bar 13, operated as hereinafter described. At the lower front portion of the casing is arranged a bank of keys A, constituting a series of operating keys, ten in number, and bearing the digits from 0 to 9, inclusive and other or special keys designated, respectively E, R and T, for purposes hereinafter explained.

Arranged within the casing are aligned spaced pairs of superposed stationary longitudinal guides 14 and 15, equal in number to the operating keys, and on which are arranged to travel sets of slides 16 and 17. 70 Connected with the lower ends of said slides is a series of slide bars 18, and connected with the upper ends of said slides is a corresponding series of slide bars 19, the bars 18 and 19 thus being arranged in pairs, the 80 bars of each pair being movable with their connecting slides in unison with each other. By this construction a series of variably movable slide frames is provided, one for each operating key, each slide frame including a lower bar 18 and an upper bar 19. Each bar 18 is provided with a longitudinal series of rack teeth 20, a stop lug 21 and a pivoted gravity dog or pawl 22 arranged in advance of said stop lug, said dog being 90 freely movable rearwardly and held from forward motion by a pin 23, while each bar 19 carries a depending series of pivoted gravity pawls or dogs 24, equal in number to the operating keys and adapted to have 95 free forward movement and held from rearward movement by stop pins 25.

Arranged within the casing beneath the sets of slides are front and rear pairs of posts 26 and 27 carrying guides 28 for a 100 transversely sliding carriage 29. This carriage 29 is normally disposed at the right-hand side of the casing laterally beyond the first set of slides, and includes a series of spaced parallel bars or frame members 30 105 arranged in pairs, each pair carrying cross pins or rods 31, 32 and 33. The pairs of bars or frame members are equal in number to the sets of slides, and each of said pairs of bars or frame members carries a series 110 of ten stop fingers 34, pivotally mounted to swing vertically on the rods 31. The fin-

gers normally lie below the plane of the bars in a substantially horizontal position and are limited in their upward and downward swinging movements by the rods 32. 5 Each finger carries a pivoted pendent latch 35 having a shoulder 36 and a beveled or cam face 37, which shoulder is adapted to engage the adjacent rod 33 to hold the finger in normal or depressed condition. 10 Springs 38 are provided to force the fingers upward when released by the latches, and springs 39 are provided to hold the latches normally in engagement with the rods 33, and as shown, these springs are 15 preferably mounted on the rods 31. The carriage is adapted to be moved intermittently to the left to successively bring the rows of stop fingers beneath a row of tumblers or knocker arms 40 carried by rock- 20 shafts 41 coupled by links 41' to pivoted levers 42 fulcrumed on a rod 42' carried by the posts 26 and connected with the respective digit-keys. These tumblers or knocker-arms are adapted when operated to engage 25 the cam faces 37 of the latches and force said latches out of engagement with the retaining rods 33, thus permitting the released stop fingers to be projected upward by the springs 38. As the shoulder 36 of each latch 30 moves out of engagement with its retaining rod 33, the cam face 37 thereof comes in contact with said rod, against which it is held by the coacting spring 39, and thus acts as a guide in the subsequent restora- 35 tion of the latch to normal position. The carriage and stop fingers constitute setting mechanism controlled by the digit-keys for variably controlling the movements of the sets of slides which adjust the printing de- 40 vices to printing position. As will be apparent, the setting fingers are projectable upward to lie in the paths of the lugs 21 and dogs 22 of the slides with which they are brought in register, to limit the degree of 45 forward travel of said slides, whereby provision is made for adjusting the characters of the printing mechanism to selective print- 50 ing position. On the forward travel of a slide the lug 21 abuts against the upwardly projected finger to hold said slide against movement beyond a predetermined position, and in such direction of travel the dog 22 is free to slide over the finger. On the back- 55 ward or return travel of the slide to normal position, the dog 22 is held from forward movement by the pin 23 and strikes the coacting finger, thus returning said finger to normal position. Springs 43 are pro- 60 vided for drawing the slides forwardly when released for travel. The slides are held from travel against the resistance of the springs 43 by a retainer bar 44 carried by arms 45 projecting from a horizontal trans- 65 verse rock shaft 46, which shaft is coupled at each end by jointed arms or toggle levers 47 and 48 to the adjacent arm 49 of a bail-shaped releasing lever 50, the cross portion of which is connected with and adapted to be depressed by the release key R. The arms 49 of said lever 50 are fulcrumed at 51 70 to the posts 27' so that when the lever is depressed the levers 47 and 48 will be elevated and the shaft 46 rocked rearwardly to throw the retainer bar 44 back to permit travel of the slides under the action of the 75 springs 43. The arms 45 are connected to the posts 27 by springs 52 which are stronger than the springs 43 and normally hold the retainer bar retracted and the slides fixed against travel. Links 53 project upward 80 from the sets of toggle-levers 47 and 48 and at their upper ends are slotted, as at 54, to slidably and pivotally engage fulcrum pins 55. Carried by said links is a yoke formed by crank arms 56 and a cross rod 57, which 85 latter passes through longitudinal slots 58 formed in a top series of slide bars 59, each carrying a longitudinal row of printing types or characters 60 corresponding to the series of digits or characters on the bank 90 of digit-keys. The printing bars are pivoted at their rear ends to the respective guides 16, as at 61, and are thus arranged to travel with the respective pairs of slides, and are movably supported at their opposite 95 ends by the links 53 and levers 47, so that by the adjustment of the slides the type characters may be selectively disposed beneath the platen roller 9 and then tilted up- 100 wardly by the rocking motion of the shaft 100 46 to bring the selected type characters into contact with the portion of the paper strip engaging the bottom of the platen roll. The rod 13 connecting the ratchet feed levers 12 is arranged in the path of upward motion 105 of the printing bars so that on the printing motion of said bars the dogs 11 will be swung downwardly and rearwardly and caused to ride over the ratchet wheels 10 110 back to feeding position, so that when the printing bars are retracted and the dogs return to normal position by gravity, the roller 9 will be turned to feed up the paper strip to the next printing line. 115

62 is an inking roller carried by pivoted arms 63 so as to be vertically movable, with the type bars. Ink may be supplied to this roller from a suitable font. (Not shown.) 120

The means for laterally adjusting the carriage 29 comprises a toothed wheel 64, having teeth equal in number to the pairs of setting slides, and which engage the teeth of a rack-sleeve 63 connected with the carriage and slidably mounted on the transverse bar or rod 28, the parts being normally 125 retained in initial position by one or more retracting springs 66. On the same shaft as the wheels 64 is a ratchet 67 normally engaged and held from retrograde movement by a pivoted gravity dog 68 having a retract- 130

ing arm 69 provided with a cam surface 70. Also engaging the ratchet wheel is a pivoted spring-pressed feed dog 71 carried by a lever 72 pivotally mounted on a depressible transverse bar 73 arranged beneath the key-levers, said bar being pivoted at one end, as at 74, to the casing and sustained at its opposite end by a spring 75. Each time a key is depressed to project a stop-finger of the series of fingers arranged in setting position, the actuated key lever engages and moves the bar 73 downward against the resistance of spring 75, which, upon retraction of said lever, returns the bar to normal position. As the lever 72 moves downward with the bar, the dog 71 slides out of engagement with the tooth with which it has been engaged and into engagement with the next succeeding tooth, so that on the upward movement of the bar the ratchet wheel 67 and feed wheel 64 are turned, the distance of one tooth, whereby the carriage 29 is moved to the left the distance of one space to bring the next succeeding row of stop-fingers into alignment with the key-tumblers. In this operation the dog 68 remains in engagement with the ratchet wheel and permits the feed wheel to have feed motion, while preventing its retrograde rotation and the retraction of the carriage by the spring 66. The lever 72 is connected by link 76 with a trip lever 77 retained in normal position by a spring 78, said lever being arranged in the path of movement of a trip lug 79 pivotally mounted on one of the arms 49 of the releasing lever 50, said trip lug normally resting on a stop 80. When the releasing lever is depressed the lug 79 strikes the lever 77 and tilts upward and passes below said lever, but on its upward movement swings said lever 77 upward thus drawing the lever 72 to the left and moving the dog 71 out of engagement with the ratchet wheel. In its outward movement the dog 71 engages the cam face 70 of the arm 69 and thereby tilts said arm and lifts the dog 68 out of engagement with the ratchet wheel, whereupon the spring 66 acts to return the carriage 29 supporting the key-controlled setting fingers to normal or initial position.

A transverse shaft 81 passes through the space between the slides 18 and 19 and the guide bars 14 and 15 and is mounted for vertical movement at its ends in slotted guide brackets 82, said shaft being carried by the arms of a bail-shaped lever 83 normally held elevated by sustaining springs 84 and connected with and adapted to be depressed by the totals key T. On said shaft 80 is loosely mounted a transverse series of adding wheels 85, equal in number to the operating keys, pairs of slides and type bars, and each having ten peripheral teeth. These wheels are normally arranged above and out 65 of engagement with the rack teeth 20 of the slides, but in position to be engaged by the dogs 24, which are adapted on the forward travel of the slides to turn the wheels distances corresponding to the ranges of travel of the slides, and upon the rearward motion 70 of the slides to ride over said teeth. Each wheel, with the exception of the first of the series, carries a cam 86, the point of which forms an elevating surface and a stop shoulder adapted to be engaged by the free end of 75 a lever 87 carried by a rock shaft 88 journaled on an upright 89 fixed to the adjacent guides 14, which shaft also carries an arm 90 provided with a dog or pawl 91 to engage the teeth of the next adjacent wheel 80 of the series, said dog being adapted on its upward motion to ride freely over the teeth of the wheel and on its downward motion, on the fall of the lever and arm by gravity, to engage a tooth and turn the wheel the 85 distance of a tooth. By this construction each forward wheel of the series when given one complete revolution will move the next or following wheel a distance of one tooth, whereby the adding wheels will be coöperatively set for adjusting the type bars to bring the type thereon into position for printing the totals of any preceding rows or columns of numerals printed on the strip. When the shaft 81 is depressed by means of 90 the totals key, the wheels will be moved downward out of the path of the dogs 24 of the bars 19 into engagement with the teeth 20 of the bars 18, so that the wheels, which may turn back to the same extent that they 95 have previously been turned forwardly, will act as regulating devices controlling the motion of the slides for adjusting the printing bars to add the previously printed sum or print up the total.

Connected with the carriage 29 is a vertically movable guard bar or plate 92 which, when the carriage is in normal position, lies in advance of all the slides. This bar or plate is movable longitudinally through an 100 opening 93 in the casing and is adapted to hold from forward movement, when the bar 44 is moved outward, all those slides which are not directly above the carriage, and in the travel of the carriage to successively pass 105 each slide to free it for movement. This bar, therefore, will hold from forward travel all the slides and type carrying bars except those for which the stop fingers are set. Connections 94 couple said bar to the lever arms 110 83 so that when the key T is depressed to depress the adding wheels are described, the bar will also be depressed to allow all of the slides and type bars to move forward for the printing of the total.

For the purpose of enabling the carriage and set-up stop fingers to be retruned to normal position when an error is made in striking any key, a retracting mechanism is provided comprising a plate 95 having at its 115 120 125 130

sides lugs 96 engaging a transverse rod or bar 97 sliding vertically in slots 98 in depending guide hangers 99, which project at their lower ends downwardly through 5 slots in the plate 95. The said plate 95 is provided with rows of retracting lugs or projections 100, which are equal in number to the rows of stop fingers on the carriage and are arranged above the respective 10 rows of stop fingers when the carriage is in normal position, as shown in Fig. 4. The error key E is operatively connected with a pivoted lever 101 with which is connected a slotted arm 102 engaging the rod 15 or bar 97, whereby the lever 101 when depressed by the error key will correspondingly depress the plate 95 to cause the lugs or projections 100 overlying the projected fingers to engage and depress or retract said 20 fingers, thereby rendering them inoperative for adjustment of the controlling slides. Carried by the lever 101 is a pin 103 engaging the slotted end 104 of a link 105 which pivotally couples the lever 101 with the lever 25 72, whereby when the lever 101 is actuated to depress the plate 95 the link 105 will be straightened out to a determined degree immediately upon the retraction of the fingers by the projections 100 to tilt the lever 72 laterally to the left in Fig. 3, thereby moving 30 the dog 71 out of engagement with the ratchet wheel 67 and retracting the dog 68, so that the spring 66 will return the carriage 29, with the setting fingers retracted, 35 to normal or initial position, so that the setting fingers may be reset for the correction of the error.

In operation, it will be understood that, with the parts in normal position shown in 40 Figs. 1 and 2, the first row of setting fingers on the carriage are disposed above the row of key-tumblers or triggers, so that upon the depression of the key representing the first numeral of a row to be printed the corresponding finger will be projected. At the same time the action of the key will 45 depress the feed bar 73, whereby the wheel 64 will be operated to feed the setting carriage to the left a distance of one row or 50 space, to bring the second row of fingers above the key tumblers. The key representing the second numeral to be printed is then depressed, thus projecting the corresponding finger in the second row of the 55 setting mechanism, and upon the release of such key the carriage is moved a second step to the left to bring the third row of fingers above the tumblers. In this manner the fingers representing the numerals of 60 a row of any number up to ten figures may be projected and the rows of set fingers brought beneath the corresponding slides, to regulate the movements of the latter for the selective adjustment of the type bars to 65 printing position. As the carriage inter-

mittently feeds beneath the slides, the inner end of the guard bar or plate 92 successively moves out of registry with each slide below which a row of fingers is brought for controlling action. After the setting 70 mechanism has thus been adjusted for regulating the action of the printing bars to print a row of figures, the release key R is depressed, as a result of which the retainer bar 44 will first be thrown rearwardly by 75 the upward motion of the links 47 and 48 to permit of the travel of the freed slides and movement of the corresponding type bars to the printing position, after which said links will be elevated sufficiently for 80 the adjustment of the links 53 to move the printing bars upward on their printing motion. Upon the release of the key R, the springs 52 return the slides and printing bars to normal position, and as the printing 85 bars drop and move backwardly the dog 11 is actuated to feed up the paper strip a regulated distance. On the backward motion of the slides, the dogs 22 depress the projected fingers to normal position, but the dogs 24 ride over the teeth of the wheels 85, leaving the latter in the positions to which they have been adjusted. As soon as this occurs the lug 79 trips the lever 77, thus retracting the pawls 68 and 71, whereupon the springs 66 return the setting carriage 29 to normal position. After a column of rows of figures has been printed on the strip by successive operations of the character described, and it is desired to 90 print the sum totals which have been added by the adjustment of the wheels 85, the key T is depressed, whereby the shaft 81 and wheels 82 are thrown downward out of the path of the dogs 24 and into engagement 95 with the teeth 20 of the slides 18, while at the same time the bar or plate 92 is depressed to free all the slides for travel. Upon the depression of the release key R, the slides will then move forward under the 100 action of the springs 66, whereby the wheels 85 will be turned backwardly until the motion of each wheel is arrested by the engagement of the stop shoulder of its cam with the lever 87, whereby each wheel is 105 permitted to rotate backwardly an extent equal to that it has previously been rotated forwardly and to arrest the motion of the slides and printing bars upon the adjustment of the latter to bring the type characters thereon representing the totals into 110 printing position, the continued motion of the release lever resulting in the totals being printed on the strip, as will be readily understood. The adding wheels will thus 115 be returned to normal position, and upon the release of the key T the springs 43 will operate to return the type bars and slides to normal position, thus resetting the machine for further use. If the error has 120 125 130

been made in setting any one of the number of a row of setting fingers to control the slides for the printing of a row of characters, the carriage and setting fingers may 5 be retracted or returned to normal position by the depression of the error key E in the manner previously described.

From the foregoing description, taken in connection with the drawings, the construction and mode of operation of my improved adding machine will be readily understood, and it will be seen that the invention provides a machine which is simple of construction and operation, which provides for 10 the direct printing of the characters upon the slip without the use of an inking ribbon, which adapts the type characters to be selectively adjusted and operated for printing in an easy and convenient manner, 15 and which provides for the ready printing of the totals of a column of figures of any length.

I claim:—

1. An adding machine comprising longitudinally and vertically movable printing bars, automatically movable slides controlling action of said bars to which the bars are pivoted at one end, springs for automatically feeding the slides forward, a pivot 25 arm for yieldingly holding the bars and slides from movement, retracting means operative to normally hold said parts from action and to return the same to normal position after actuation against the resistance of said springs, rocker arms movable with the said pivot arm, key-controlled means for governing the action of said arms, means slidably and pivotally engaging the printing bars for raising and lowering the 30 same in unison, and connections between the rocker arms and said means.

2. An adding machine including a series of printing devices, a series of automatically movable setting slides controlling the same, key-controlled means for regulating the degrees of motion of the setting slides when released, key-controlled retaining means for normally holding the setting slides from action and for freeing them for movement, 45 a series of adding wheels, means upon the setting slides for turning the wheels to predetermined degrees governed by the extent 50

of motion of the slides, a movable retaining bar for holding all the slides from movement and successively releasing each slide, 55 and key-controlled means for simultaneously moving said bar out of the path of motion of the slides and adjusting the adding wheels into engagement with the setting slides to control the motions of said 60 slides for a totals printing action.

3. An adding machine comprising longitudinally and vertically movable printing bars, automatically movable slides controlling the action of said bars, springs for 65 automatically feeding the slides forward, a pivot arm for yieldingly holding the bars and slides from movement, retracting means acting upon said arm for returning the parts to normal position, said retracting means 70 being operative to return the aforesaid parts to normal position after actuation against the resistance of said springs, rocker arms movable with the said pivot arm, key-controlled means governing the action of 75 said arms, and connections between said rocker arms and printing bars for moving said bars to printing position.

4. An adding machine including a series of printing devices, a series of spring actuated setting slides controlling the same, key-controlled means for regulating the degrees of motion of the setting slides when released, key-controlled retaining means for normally holding the setting slides from action and 80 for freeing them for movement, a series of adding wheels, means upon the setting slides for turning the wheels to predetermined degrees governed by the extent of motion of 85 the slides, a horizontal transversely movable retaining bar for holding all the slides from movement and successively releasing each slide, and key-controlled means for simultaneously moving said bar out of the path of motion of the slides and adjusting 90 the adding wheels into engagement with the setting slides to control the motions of said slides for a totals printing action.

In testimony whereof I affix my signature in presence of two witnesses.

HERBERT H. BLACKWELL.
